UNITED STATES PATENT OFFICE.

DELOS P. HEATH, OF PEORIA, ILLINOIS.

MECHANICAL REFRIGERATION APPARATUS.

Application filed August 9, 1926. Serial No. 127,988.

This invention relates to mechanical refrigeration apparatus. It is an object and purpose of the present invention to construct an apparatus of the character indicated, providing a refrigerating unit including electric motor for driving the compressor of the unit, the same being automatically started and stopped in accordance with variations in pressure in the low pressure or expansion 5 part of the line which carries the compressible and expansible refrigerating fluid, together with a condenser coil adapted to be air cooled, and a radiator of cast iron in which the compressed fluid is expanded with a resulting absorption of heat from the surrounding atmosphere around the radiator for the production of refrigeration. A further object of the invention is to provide a novel construction and assembly of mechanical refrigeration unit, one in which the condenser coil is supported in a simple and novel manner, and is cooled by air blown thereover from a fan forming a part of the drive pulley of the compressor, the unit as a whole being of very durable and practical construction. Many other objects and purposes than those stated will be apparent as understanding of the invention is had from the following description, taken in connection with the accompanying drawings, in which,

Fig. 1 is a side elevation of the complete refrigerating unit, the radiator being shown in vertical section.

Fig. 2 is a diagrammatic outline in elevation of the unit.

Fig. 3 is a plan view of the motor, compressor, condenser coil and control box, showing the same supported on a horizontal platform, and

Fig. 4 is a vertical section taken substantially on the plane of line 4-4, of Fig. 3.

Like reference characters refer to like parts in the different figures of the drawings.

In the construction shown, a horizontal platform 1 of wood is used, the same being of rectangular shape. At each end thereof supporting members are used, each including a front substantially vertical leg 2 and a rear similar leg 3 connected at their upper ends by an angle bar 4, the width of the platform 1 being less than the length of the bars 4 so that a space is left between the rear edge of the platform and an angle bar 5 connecting the rear ends of the bars 4, as shown in Figs. 3 and 4. The angle bar 5 is located with a

flange 5^a in a vertical plane in front of which is the condenser coils 6 of the unit. These coils are located in continuous superimposed relation, the uppermost of the coils being located a considerable distance above the bar 5 and the lowermost being below said bar, as shown in Figs. 1 and 4.

This condenser coil construction, at its rear sides bears against two pairs of vertical bars 7 secured adjacent the ends of the angle bar 5. Two pairs of clamping bars 8 lie against the inner sides of the coils, one in front of each pair of bars 7, and are permanently secured thereto, thereby securely clamping the rear side of the coil construction and holding it vertical. A bar 9 of metal is attached at its front lower end to the upper side of the platform 1 and therefrom extends diagonally upward and to the rear for a distance, being then bent to make a horizontal section 10, at the rear end of which it is turned vertically upward, as indicated at 11. Two pairs of clamping bars 12 and 13 are vertically disposed at the front and back respectively of the front side of the coil construction and permanently clamped thereagainst, the section 11 of the diagonal bar 9 previously described lying against the upper end portion of the bars 12 and having secure attachment thereto. The coil construction 6, accordingly, is very securely held on the support therefor, its lower portion extending downwardly through the rectangular opening between the rear edge of the platform 1 and the bar 5.

The coil construction at its upper end has a pipe 14 which connects with the head 15 of a compressor 16 mounted on the platform 1 in front of the coil construction 6. The compressed fluid goes from the compressor to the coil construction through pipe 14 and the regulation of the compression of the fluid is accomplished through the adjusting member 15^a shown in Figs. 1 and 4. The shaft 17 of the compressor extends rearwardly and at its rear end a short distance in front of the condenser coils 6 is equipped with a fan 18 around the outer ends of the blades of which a grooved rim 19 is located and secured. An electric motor 20 is attached to and supported by the platform 1 near one end thereof, having a drive pulley at one end of its shaft around which and the rim 19 an endless belt 21 is placed drive the fan and the compressor 22 is placed drive the fan and the compressor from the motor. A metal shield 22 of the

curved form shown lies over the fan, belt and pulleys being attached at its ends to the bars 4 back of the rear edge of the platform. The fan 18 and the rim 19 around it extend downwardly in the opening back of the platform. The air blown by the fan rearwardly serves to cool the condenser coil construction, disseminating the heat which comes from the compression of the refrigerant fluid as it is forced into the condenser coil.

At the lower end of the said coil construction 6 a pipe 23 leads forwardly and upwardly over the upper side of the platform, connecting at its front end to a coupling 24 attached to the platform in which a regulating stem 25 is mounted so as to control the passage of the fluid to the pipe 26 connected at its lower end with said coupling. Pipe 26 extends upwardly and at its upper end joins with a float chamber 27 which is of elongated form, at one end being enlarged, as indicated at 27^a, joining with which is the narrow elongated portion 27^b, at the end of which a valve seat 28 is positioned at its lower side. A ball float 29 is located in the enlarged portion 27^a fixed at one end of a rod 30 which lies within and lengthwise of the portion 27^b of the chamber. The rod 30 is pivotally connected at its other end at 31 to the said chamber and carries a vertical valve pin 32 near such pivot which is elevated with the elevation of the ball 29 so as to open the passage through the valve seat at 28. The fluid thereupon passes from the float chamber through a U-shaped pipe 33 to the radiator 34 which is of cast iron with outwardly extending radiating vanes at its sides, within which is a rectangular shaped inner radiator element 35, the fluid passing through a passage 36 from pipe 33 to the relatively narrow spaces between the inner and outer radiator elements, expanding in said radiator and changing from liquid to gaseous form with the consequent absorption of heat from the surrounding atmosphere.

In the upper end of the radiator is a chamber 37 to which the gaseous refrigerant fluid is carried and from which it passes through a screen 38 to a return pipe 39 and thence downwardly to a connection 40 attached to the compressor 16, the gaseous fluid being taken into the compressor and compressed to liquid form and delivered to the condenser coils 6. The screen 38 is very useful in order to preclude the passage of any solid matter to the pipe 39 which is likely to be present in the interior of the cast iron radiator from which all of the sand core usually cannot be completely cleaned after casting.

When the compressor 16 is not operated, the passage of the liquid refrigerating fluid from the condenser coils to the radiator, with the expansion of the liquid to gaseous state, serves in time to increase the pressure in the radiator and in the pipe 39 and connection 40,

which pressure is transmitted through the small lead pipe 41 connected with the part 40 to an automatic switch control housed in a control box or housing 42 mounted above and supported by the platform 1. The effect of the building up of pressure is to throw the switch when the pressure reaches a certain and predetermined amount and complete an electric circuit in which the motor 20 is located, thereby starting the motor in operation and taking the gaseous fluid from the radiator, compressing it and delivering it in liquid form to the coils 6. The electric wiring between the control housing and the motor is shown at 43. The construction of the automatic switch control is not specifically shown in the present application, it being the subject matter of a copending application for patent. The compression of the gaseous fluid taken from the radiator 34 serves to reduce the pressure of the gas, and when the same has been reduced to a predetermined and desired amount, the switch is again thrown to circuit breaking position, stopping the motor from operating.

The construction described is very practical. The single support for the entire mechanism, excepting the radiator makes it possible to build and assemble the construction very readily and economically. The air cooling of the condenser coils is accomplished in a simple and efficient manner. The supporting of the coils is simple and practical. The control of the automatic starting and stopping of the motor from the low pressure side of the condenser is of value. It is possible to defrost the radiator between successive cycles of operation of the motor, the temperature in the radiator being raised to above the freezing point a short time before the motor is cut in to operate the compressor so that any frost or ice accumulating on the radiator is melted, this obviating the necessity of periodically defrosting the radiator as required in other systems. A compact, economically built, efficient and durable refrigerating unit is produced and one which has proved its value in service. The appended claims define the invention, which is to be considered comprehensive of all structures coming within their scope.

I claim:

1. In combination a horizontal platform, bars secured at opposite ends transversely of the platform and extending beyond the rear edge thereof, supporting feet extending downwardly from the ends of said bars, a third bar located horizontally between and connected to the rear ends of the first bars whereby an opening is provided between said rear end to the platform, a condenser coil construction located vertically in front of and connected to said third bar having its lower portion extending below the lower side of said platform, and an electric motor, a compressor driven

thereby and a control box for the motor mounted upon said platform in front of the coil.

2. In construction in the class described, a horizontal platform of rectangular outline, bars having supporting feet extending downwardly from their ends connected to and located transversely of said platform at its ends, said bars extending rearwardly beyond the rear edge of the platform, a third bar located parallel to the rear edge said platform and connecting the rear ends of said first mentioned bars, a condenser coil structure comprising a plurality of coils located one over the other disposed vertically in front of and secured to said third bar, the lower coils of said coil construction extending downwardly through the opening between said third bar and rear of the platform, a compressor carried by said platform, a fan secured on the shaft of said compressor in front of the coil construction and extending at its lower portion through the opening between the platform and the third bar, an electric motor for driving the compressor carried on said platform, and means for driving the compressor from said electric motor.

3. In combination, a horizontal platform, transverse supporting bars secured at the ends of said platform and at their rear ends extending a distance back of the rear edge of said platform, feet extending downwardly from said bars, a third bar connecting the

rear ends of the first mentioned bars, a condenser coil construction formed of a plurality of superimposed coils located in the front of the third bar, the lower portion thereof extending below the platform, means connecting the rear side of the coil construction to said third bar, a brace member attached at one end to the platform extending upwardly and connected to the upper end of the coil construction, a compressor carried by the platform in front of said coil construction and having a rearwardly extending shaft, a fan on the shaft, a grooved rim around the fan, said fan and rim at their lower portions lying below the platform, an electric motor on said platform, and means passing around said rim from the electric motor for driving the compressor.

4. In a construction of the class described, a horizontal platform, a frame having legs supporting said platform, a compressor and motor mounted on said platform, a condenser coil, vertical bars clamped to said condenser coil and attached to said frame, vertical bars clamped to said condenser coil and supported upon said platform by an inclined brace, and a guard shielding parts of said compressor and motor, said guard being semi-circular in form and fixed at its ends to said platform and supported at its middle by said inclined brace.

In testimony whereof I affix my signature.
DELOS P. HEATH.
